CALCULATING MACHINE.

Application filed September 7, 1922. Serial No. 588,793.

This invention relates to calculating machines, and has for its primary object to enable the performance of the operation of division, whether the factors be single or multiple place, without any necessity for the person operating the machine keeping constant watch over the various numeral or counter wheels, lest the operation be continued after the remainder has become less than the divisor and with the result that an erroneous result would be indicated.

In accordance with the invention, provision is made whereby the operation of the machine is arrested automatically as soon as the remainder drops in value below the divisor, thereby requiring the setting of one factor, in the present instance—the dividend—to be transferred to the adjacent ordinal places, before the operation can be resumed. After each shift, the operation of the machine will be arrested whenever the remainder becomes less than the divisor and, when the operation is arrested during the final shift, the quotient will be indicated on one series of numeral wheels and another series, on which the dividend was set at the beginning of the operation, will show the remainder, if any. By the invention, the operation of division, on a calculating machine is greatly facilitated and simplified and any necessity for mental work by the operator is greatly reduced while, at the same time, the liability to error is practically eliminated, since the operator cannot continue to operate the machine when the dividend of ordinal places corresponding to the divisor has been reduced to a value below the divisor.

In addition to the general objects recited above, the invention has for further objects such other improvements or advantages in construction and operation as may be found to obtain in the structures and devices hereinafter described or claimed.

In the accompanying drawings forming a part of this specification and showing, for purposes of exemplification, a preferred form and manner in which the invention may be embodied and practiced, but without limiting the claimed invention specifically to such illustrative instance or instances:

Figure 1 is a plan view of a calculating machine embodying the improvements of the present invention;

Figure 2 an enlarged top plan view having most of the top plate of the casing broken away and having parts omitted in some of the orders to show the interior construction of the machine;

Figure 3 is a vertical section taken longitudinally along the front of the machine;

Figure 4 is another longitudinal vertical section but taken in a plane to the rear of Figure 3;

Figure 5 is a transverse vertical section of the machine;

Figure 6 is another transverse vertical section of the mechanism in the rear of the machine but taken on a plane to the right of Figure 5;

Figure 7 is a perspective view showing one order of the mechanism for locking the machine when the value of the remainder is reduced below the divisor;

Figure 8 is a perspective of a mechanism for locking the machine against operation except when the carriage is in operative relation to other parts, as hereinafter described; and

Figure 9 is a detailed section taken on the line 9—9 of Figure 3 and showing part of a mechanism for preventing movement of the carriage out of its operative position during the movement of the operating crank.

In its present embodiment and for the sake of simplicity in construction and in the ensuing description, the invention has been incorporated in the very ancient type of calculating machine originally designed by Gottlieb Leibnitz about the year 1690 A. D. and exemplified in various forms in the prior British Letters Patent to Thomas de Colmar, No. 13,504 of A. D. 1851, and the Letters Patent of the United States to Robert Rein, No. 897,659, dated September 1, 1908. For convenience, the present description will be confined to the embodiment of this invention in a machine of the Leibnitz or Thomas type. The broadly novel features of the invention, as pointed out in the claims, may be applied to calculating machines of other types. Hence, the invention is not limited in its scope to the particular construction and embodiment herein described as an illustrative example.

As the details of the "multiple-cylinder type" of calculating machine are well-known and may be readily understood from the

prior British Letters Patent of Thomas de Colmar and the prior U. S. Letters Patent of Rein, both hereinbefore referred to, a brief description of the general features of this type of machine, and such parts as are directly concerned with the operation of the present improvements will be ample for an understanding of this invention.

As shown, the machine comprises a stationary casing 11 and carriage 12 shiftable longitudinally of the casing. The carriage 12 carries the accumulator showing the result when the arithmetical operation is accumulation i. e., in addition or multiplication, and also in subtraction; the carriage also supports another series of numeral wheels for indicating another factor, for example, the multiplier, in multiplying and the quotient when performing division. The casing 11 supports the actuator mechanism and for this purpose contains a suitable frame 13 constituted of upright supporting plates or members for the various orders of the actuator mechanism.

The actuator mechanism comprises a plurality of drums or cylinders 14, one for each order of the machine, the said drums extending parallel with each other and transversely of the stationary casing, being mounted on the squared shafts 15. At their forward ends, the shafts 15 are respectively provided with bevel gears 16 in mesh with bevel gears 17 on the main drive shaft 18, the latter extending longitudinally of the casing in the front of the machine, as shown best in Figure 2. This main drive shaft 18 has at its extreme right hand end (viewing Fig. 2) a bevel gear 19 meshing with a bevel gear 20 at the lower end of the vertical operating shaft 21. At its upper end, above the top casing plate, the operating shaft 21 is provided with a hand crank 22, which, when turned in a clockwise direction, (viewing Figs. 1 and 2) operates, through the shafting and gearing just mentioned, to turn the actuator drums 14 in unison in a counterclockwise direction.

Each actuator drum 14 is provided on its periphery with a series of nine graduated or stepped teeth, arranged in the usual manner in accordance with the principal employed by Leibnitz and Thomas, the nine teeth representing the digits 1 to 9 inclusive and presenting a progressively increasing number of actuating teeth in planes taken transversely through the drum at intervals from front to rear of the machine. With this construction, the transmitting pinion, if set (as will be presently described) at the extreme digital setting towards the front of the drum, will be engaged only by the actuator tooth of longest length and will therefore be imparted only a one-step movement during a complete revolution of the drum. If set at the extreme rear of the

drum, the transmitting pinion will be engaged by all nine teeth and will then receive a nine-step movement each time the drum makes a complete revolution. When set at intermediate distances, the transmitting pinion will be actuated a number of steps corresponding with the number of the teeth which it can engage in its setting, the intermediate intervals corresponding to the digits between 1 and 9.

A transmitting pinion 23 is provided for each drum 14 and the several transmitting pinions are mounted to slide on squared shafts 24 extending parallel with the axes of the respective drums. The transmitting pinions 23 are each mounted at the bottoms of the slideable setting devices 25 having portions which project upwardly through slots 26 in the top plate of the main casing. Each setting device is provided at its upper end, above the top plate of the casing, with a finger knob 27 and with a pointer 28 to cooperate with the series of digits "1" to "9" inclusive and "0" indicated along the side of the companion slot 26, the indication "0" being at the extreme forward end of the slot and the digit "9" being at the extreme rear end of the slot. When the setting device is adjusted so that the indicator 28 is opposite "0" the transmitting pinion 23 is positioned beyond the forward end of its corresponding drum 14 and thus will receive no motion from said drum. Adjustment of the setting device 25 so that the pointer is opposite any one of the digits positions the setting device for engagement with a like number of teeth of the drum 14, with the result that a single rotation of the drum 14 will impart to said transmitting pinion a stepped movement corresponding with its digital setting.

As shown especially in Figs. 4 and 5, the stepped teeth do not extend clear around the periphery of the drum, although a complete rotation of the drum is required to impart a predetermined movement of the transmitting pinion in any setting. A Geneva motion is provided to operate between the drum shaft 15 and the transmitting pinion shaft 24, for the purpose of locking the shaft 24 against rotation, except when the tooth portion of the drum periphery is in position for meshing with the transmitting pinion. This will occur toward the end of an operative rotation of the drum 14. Mounted on each transmitting shaft 24 is a Geneva wheel 29 provided with ten arcuate cam surfaces 30 on its periphery. A cooperating cam 31 is slidably mounted on the corresponding drum shaft 15 and is provided with a peripheral portion 32 concentric with the axis of rotation of said shaft 15 and with an eccentric cut away peripheral face 33. Except when the toothed portion of the companion drum 14 is in position for meshing with the transmitting pinion 23, the concentric peripheral

face 32 of the cam 31 engages one of the arcuate cam surfaces of the companion Geneva wheel 29, with the result that the Geneva wheel 29 and its transmitting shaft 24 is locked against rotation. However, when the drum 14 has been rotated so as to bring its toothed portion into position for being meshed with the transmitting pinion, the cut away part 33 of the cam 31 has been moved to release the Geneva wheel and to permit a movement of the transmitting pinion 23 for an amount determined by its setting.

Each transmitting shaft 24 extends rearwardly of the main casing 11 and is provided at its rear end with a pair of beveled gears 34 and 35. The said gears 34 and 35 are mutually connected by a hub 36, the latter being provided with a peripheral groove 37. The gears 34, 35 together with their connecting hub 36 are slidably mounted on the transmitting shaft 24 and the forward gear 34 is intended to impart forward rotation to the corresponding accumulator wheels 38 while the other gear 35 is intended to impart rearward or backward rotation to said accumulator wheel. According to the design of the illustrated type of calculating machine, the forward rotation of the accumulator wheel is employed for an accumulative arithmetical process, such as addition or multiplication and the rearward or backward rotation of the accumulator wheel is employed for the opposite arithmetical process, namely subtraction or division.

The accumulator wheels 38 are disposed in series extending longitudinally of the carriage 12 and each accumulator wheel is mounted on a vertical spindle 39 journaled in the top plate 40 of the carriage and provided at its upper end with a finger knob 41 permitting a setting of the accumulator wheel, for purposes which will presently appear. The face of each accumulator wheel 38 is provided with the digits "1" to "9" inclusive and "0", which will show through a companion sight opening 42 provided in the top plate of the carriage. The spindle 39 of each accumulator wheel is provided at its lower end, beneath the top plate 40 with a beveled gear 43 adapted to mesh with either the gear 34 or the gear 35 of the transmitting shaft 24. A rock bar 44 extends longitudinally of the machine and seats in the peripheral grooves 37 of the hubs 36 of the various orders of the machine. The rock bar 44 is mounted at its ends on rock arms 45 and may be rocked rearwardly by a setting handle 46 to bring the entire series of pinions 34 into mesh with corresponding orders of the accumulator gears 43, or forwardly to bring the entire series of reverse rotation gears 35 into mesh with corresponding gears 43. A forward setting of the handle 46 by meshing the gears 35 with the gears

43 sets the machine for subtraction or division, while a rearward setting of said handle 46 by meshing the gears 34 with the gears 43 sets the machine for addition or multiplication.

Carrying mechanism is provided in each accumulator mechanism for the purpose of actuating the accumulator of the next higher order of the machine whenever a carry is to go over from a lower order. A carrying cam 47 is fixed on the spindle 39 of each accumulator wheel 38, the said carrying cam 47 having an operative throw with respect to the carrying mechanism of the next higher order, whenever the accumulator wheel 38 of the next lower order passes from "9" to "0." Pivottally mounted so as to be in the path of the respective carrying cams 47 are the cam shifting levers 48 adapted to be moved by the operative impulses of the carrying cams of their next lower orders and by such movement to shift mechanism in the next higher orders for the purpose of imparting a carrying throw thereto. The cam 31 on each drum shaft 15 is provided at its forward end, see Fig. 3, with a carrying-release cam 49 adapted to permit a one step movement of the transmitting shaft 24 at the close of the normal accumulative movement imparted to said shaft by the corresponding drum 14 and transmitting pinion 23. The cam 31 is slidable toward the rear of the machine, such sliding movement being effected by an abutment 50 which moves in unison with the cam and is adapted to be actuated by a carrying gear shift lever 51 whenever a throw is imparted to the cam shifting lever 48 by the carrying cam 47. Mounted on the transmitting shaft 24 is a carrying gear 52 which is adapted to receive a carrying impulse from a carrying arm 53 on the drum shaft 15 and slidable rearwardly with the cam 31 when the latter is shifted by the operation of the carrying gear shift lever. The rearward movement of the cam 31 and the carrying arm 53 positions the cam face 49 in registry with the Geneva wheel 29 to permit the carrying throw, as hereinbefore explained and concurrently positions the carrying arm 51 so that the movement of the shaft 15 will cause said arm 53 to engage a tooth of the carrying gear 52 and thereby to impart a one step movement to its corresponding accumulator wheel 38. Except when a carrying impulse has been released by the movement of the carrying cam 47 of a lower order, both the cam face 49 and the carrying arm 53 are out of registry with the Geneva wheel 29 and the carrying gear 52, so that no carrying impulse will be imparted to the accumulator by the rotation of the drum shaft 15.

A cam 54 on the shaft 15 and engageable by a pin 55 projecting from the longitudinal vertical frame plate shifts the cam 31

and the carrying arm 53 back to normal position, during the further rotation of the drum shaft 15 after the carrying impulse. The like forward movement of the abutment 50 restores the gear shift lever 51 and the cam shifting lever 48 to normal position.

A second series of numeral wheels 56 is mounted in the top plate of the carriage. Each of said numeral wheels 56 is provided 10 with a vertical spindle 57 journaled in the top plate and having at its end above said plate a finger knob 58. The indications of the respective numeral wheels 56 show through sight openings 59 in the top plate 15 of the carriage. Each numeral wheel 56 is provided with two sets of digits from "1" to "9" inclusive and with the indication "0," one set of digits denoting a forward accumulative movement of the main accumulators 38 and the other set of digits denoting 20 a reverse operation of said accumulators 38, such as would be employed in subtraction or division. Each numeral wheel 56 is provided with peripheral gear teeth 60 to impart a step-by-step rotation to the wheel. The drum shaft 15 of the first order to the right of the machine is geared with reduction gearing 61 to effect a one step movement 25 of a toothed wheel 62 for each complete rotation of the operating crank 22 and the several drum shafts 15 of the machine. The carriage 12 supporting the main accumulators 38 and the numeral wheels 56 is both pivotally and slidably mounted on a longitudinal rod 63; and, with this construction, 30 any one of the numeral wheels 56 may be selectively shifted so that its gear teeth 60 are brought into registry with the toothed wheel 62. This will rotate the numeral wheel 56 one numeral space for each complete rotation of the operating crank 22.

Zeroizing mechanism is provided for the purpose of restoring the main accumulators 38 and the numeral wheels 56 to zero or to 45 normal. The main accumulators are provided respectively with the zeroizing gears 63' and the numeral wheels 56 with zeroizing gears 64. Reciprocating bars 65 and 50 66, provided with rack teeth are adapted respectively to be brought into mesh with the series of zeroizing gears 63' and 64. The reciprocation of said bars when so enmeshed with their respective gears will restore the accumulators 38 and the numeral wheels 56 55 to zero. The zeroizing operation is accomplished by rotating the zeroizing handle knobs 67.

Such is, in brief outline, the manner in 60 which accumulations and carry impulses are imparted in the calculating machine of the type selected for illustrating the present invention.

If it be desired to perform an accumulative arithmetical function on the machine 65 just described, the setting handle is moved

toward the rear of the machine, so that it will be opposite the symbol "Add or mul." This, as hereinbefore explained, sets the machine for effecting forward rotation of the main accumulators 38 by positioning the 70 forward transmitting gears 34 to mesh with the accumulator gears 38. In performing addition, the carriage may be shifted arbitrarily so that any desired orders of the main accumulators are in operative relation 75 with respect to any desired orders of the actuator mechanisms. It will be found convenient however, as indicated in Fig. 1, to position the carriage so that the extreme right hand order of the accumulator mechanism corresponds with the extreme right hand order of the actuator mechanism. Before commencing the operation, the accumulators 38 are set to normal or zero. The digits of the several orders of each number 80 to be added may then be successively set up by shifting the setting devices 25 and the numbers successively transferred to the accumulators 38 by successive operations of the operating crank 22. After each setting 85 of a number to be added the operating crank 22 will be given a complete rotation, the carrying mechanism operating during the motion of said crank to transfer, whenever necessary, carrying impulses from lower orders to the next higher orders. When all of the numbers have been set up and successively transferred to the accumulators 38, 90 the sum will show through the sight openings 42.

If it be desired to perform multiplication with the machine, the accumulators 38 are first reset to zero, and one of the factors of the example to be performed, such as the multiplicand, may be set up in the actuating mechanism by moving the setting devices 25. The lowest order of the multiplicand may appear at the extreme right of the machine, if desired, although this is not necessary if all orders other than those containing the multiplicand setting be set at zero. The operation of multiplication may be performed either beginning with the lowest order of the multiplier and continuing 105 the multiplication upwardly until the highest order is completed, as is customary in performing multiplication mentally, or the process may start with the highest order of the multiplier and the operation continued 110 downwardly until the units order of the 115 multiplier has completed its multiplying function. In performing multiplication according to the last mentioned method the carriage is first shifted toward the left so that the top figure of the multiplier will correspond with the lowest figure of the multiplicand set up in the actuating mechanism. When multiplying from right to left however, the carriage is positioned initially so 120 that the lowest figure of the multiplier cor- 125 130

responds with the lowest figure of the multiplicand. Whatever method be employed, the operating crank 22 is rotated a number of turns corresponding with the digital value of each order of the multiplier and when each ordinal multiplying function has been completed the carriage is shifted one ordinal space to bring the next accumulators, whether to the right or to the left, in operative relation with the multiplicand setting. When all the orders of the multiplier have been exhausted, the product will show in the eight openings of the main accumulators 38.

15 In accordance with the principal of operation of the calculating machine just described, the arithmetical calculations of subtraction or division are performed by imparting rotations to the main accumulators 38 reversely with respect to the arrangement of the digital values on said accumulators. To perform either subtraction or division the setting handle 46 is adjusted toward the front of the machine, as shown in Fig. 1, so 20 that said setting handle is opposite the symbol "Subt or div," whereby the rotation of the operating crank 22 will rotate the accumulators 38, reversely through the actuating mechanism, instead of forwardly as in 25 addition or multiplication.

To perform subtraction, one factor of the problem, such as the minuend, may be set up on the series of accumulators 38, preferably from right to left of the machine for as many 30 ordinal places as there are ordinal places in the minuend. The subtrahend may be set up in the actuating mechanism by proper shifts of the setting devices 25, and the carriage 12 is adjusted so that the lowest ordinal position 35 of the minuend corresponds with the lowest ordinal position of the subtrahend. Then by turning the crank 22 for one complete rotation the various orders of the minuend will be respectively turned backwardly each for a 40 number of steps corresponding with the digital values of the subtrahend set up in the actuating mechanism. Should the carrying mechanism operate in any of the orders of the machine during the subtraction, the carriage 45 impulse will operate to subtract a unit from the next highest order instead of adding a value as in multiplication or addition.

The machine has the further capacity of 50 performing the operation of division, and it is the object of the present invention to enable the performance of division, not only substantially without mental effort by the operator, but also practically to eliminate any possibility of error in performing the 55 calculation. To perform division, the dividend is set up on the accumulators 38 and the divisor is set up in the actuating mechanism by adjusting the setting devices 25. The carriage is positioned so that the highest 60 number of the dividend is in the same

order of the machine as the highest number of the divisor. For example should it be desired to divide 8,972,463 by 3,549, the divisor will be set up from left to right in the orders of setting devices 25 as shown in Fig. 1 and the dividend will be set up in the accumulators 38. The carriage will be initially positioned so that the number "8," the highest order of the dividend is in the same order of the machine as the number "3," the highest order of the divisor. In order to divide, the setting handle 46 is set at the symbol "Subt or div" and the operating crank 22 is rotated for as many revolutions as can be made until the first four figures of the dividend become less than the divisor. Whenever this occurs, the carriage must be shifted toward the right an ordinal space and the subtraction operation repeated until the remainder in the effective orders is less than the divisor. The operation of first subtraction for as many operations as can be made and then the shifting of the carriage is continued until the last place of the dividend corresponds with the last place of the divisor and the final remainder, if any has been reduced to a value below that of the divisor. The quotient will show in the set of numeral wheels 56 read from left to right of the machine and the remainder, if any, will show in the accumulators 38. If there be no remainder all of the previously set accumulators 38 will show the symbol "0" through the eight openings.

The main operating shaft 18 of the machine is provided with ordinal stop abutments 68, any one of which may cooperate with an individual stop mechanism to arrest the motion of the shaft 18, should the remainder drop in value below the divisor. The stop mechanisms are respectively controlled not only by both factors of the example in the orders in which they operate but also by each other so that the mere dropping in value of one digit of the remainder below the corresponding ordinal digit of the divisor, although the entire remainder is still greater than the divisor, would not result in arresting the operation of the machine. In other words, the control of the ordinal stop mechanisms by each other is such that the value of the entire remainder must be less than the value of the entire divisor in the corresponding ordinal places before any of the stop mechanisms can be released to arrest the operation of the machine.

Pivotedly mounted at 69 to the front face of a vertical supporting plate 70 and arranged in the several orders of the actuating mechanism are stop levers 71. Each stop lever 71 is provided with a depending stop arm 72 adapted to be shifted into the path of movement of the corresponding abutment 68 to arrest the motion of the main operating shaft 18 when the stop lever

is turned about its pivot in a clockwise direction, as viewed in Fig. 3. With the exception of the stop lever in the highest order, each lever is furthermore provided with a 5 downwardly inclined trigger arm 73 extending to and beneath the depending arm 74 of a bell crank trigger 75, located in the next higher order. These bell crank triggers 75 are provided in each order of the 10 machine with the exception of the lowest order and are pivoted on the pivots 69 of their respectively cooperating stop levers. The other arms 77 of the bell crank triggers 76 are connected by springs 78 with the dependent stop arms 72 of their respective stop levers. With this construction, no stop lever in a lower order can move to its shaft-arresting position unless the trigger 75 of the next higher order has been moved to a 15 position to release the trigger arm 73 of the lower order and consequently the operation of each stop lever is controlled by the trigger mechanism operated by the stop lever of the next higher order. The stop 20 levers are furthermore provided with upwardly projecting release arms 79 terminating in bifurcations 80 in which seat pins 81 projecting from the forward ends of the lower members 82 of the stop-setting lever 25 device 83.

Each stop-setting lever device is constituted of an upper lever member 84 and the before-mentioned lower lever member 82, both lever members being pivoted together 25 at 85 near the rear end of the upper lever member 84. The stop-setting lever devices are respectively arranged in the various orders of the machine and extend horizontally across the top of the actuating mechanism 40 and along the path of movement of the before-mentioned actuating mechanism setting devices 25. The upper lever members 84 of the respective stop-setting lever devices are pivoted at their forward ends respectively 45 to uprights of the fixed vertical plate 70, as shown at 86. The lower lever member 82 of each lever device extends rearwardly beyond the upper lever member 84 and is provided at its rearmost end with a feeler hook 50 87 adapted for cooperation with a stepped disk 88 of the corresponding accumulator wheel 38. Each stepped cam 88 is rotated in unison with its corresponding ordinal accumulator 38 and is provided with ten steps 55 or faces 89 one for each of the ten symbols of the accumulator. The steps 89 of each disk 88 are disposed at progressively increasing distances from the axis of rotation of the corresponding accumulator with the step 60 of greatest distance or axial dimension, corresponding to the "0" point of the accumulator and with the step 89 of the least distance corresponding to the "9" point of the accumulator. These stepped disks 88 have 65 the function of imposing restrictions in vary-

ing degrees on the movement of the feeler hook 87 toward the center of their respective accumulators, the amount of restriction being determined by the position of the accumulators. 70

Along its lateral edge facing the setting device 25, the upper lever member 84 of each stop-setting device is provided with ten stepped abutments 90, said abutments 90 being disposed at progressively increasing distances from front to rear of the machine with respect to the transverse path of movement of the setting devices 25. In other words the stop abutment at the "0" point of the setting device 25 is so located as to be substantially in contact with the body of said setting device, when the lever member 84 is at rest, whereas the stop abutment located at the "9" point of the setting device, is at its maximum distance from the body of 80 said setting device to permit a maximum movement of the stop-setting mechanism toward the setting device and toward the before-mentioned stepped cam 88. 85

In the operation of the machine for performing division, the several stop-setting mechanisms are oscillated toward and from their respective stepped cams 88, the degree of oscillation of the individual setting mechanisms being determined by the adjustment 90 of the respective setting devices 25. The oscillation of the stop-setting mechanisms is effected by means of a reciprocating bar 91 extending longitudinally of the machine and provided with slots 92 through which both 100 members 82 and 84 of the stop-setting mechanisms extend, as shown in Figs. 4 and 8. The slots 92 permit a yielding movement of the stop-setting mechanisms relatively to the bar 91, as will be presently described. At 105 its right hand end (Fig. 4) the reciprocating bar 91 is provided with a stud 93 which enters a bifurcation 94 in the upper arm of a rocker assembly 95 mounted on a transverse shaft 96. The rocker assembly 95 is 110 provided with a pair of arms 97 having rollers 98 and 99 which respectively engage the cam surfaces 100 and 101 of a cam assembly 102 that is slidably mounted on the drum shaft 15 in the first order to the right of the 115 machine. The cam 101 is shifted into position for engaging the arm 99 of the rocker assembly by the movement of the shift bar 44 in setting the machine for division or subtraction. For this purpose the cam 101 is 120 connected with said shift bar 44 by means of an extension 103. When the machine is set for addition or multiplication, the cam 101 is moved out of its engaging position with respect to the arms 99 of the rocker assembly 125 so that the reciprocating bar 91 and the several stop-setting mechanisms remain stationary during addition or multiplication. With the exception of the stop-setting mechanism in the lowest order of the machine, the sev- 130

eral stop-setting mechanisms are connected by springs 104 with lugs 105 depending from the reciprocating bar 91. The lowest order stop-setting mechanism is connected by a spring 106 directly to said reciprocating bar 91. With the construction just described and shown, and assuming that the machine has been set to perform division, the turning of the crank 22, through the cams, the rocker assembly and the reciprocating bar 91, will impart a left to right and return movement of each of the various stop-setting lever mechanisms 83 of the machine, said movement occurring toward the end of an operative rotation of the crank 22, and after all movement of the accumulators 38 has ceased.

As hereinabove stated, in performing division the dividend is set up on the accumulators 38 and the divisor in the actuating mechanism by the setting devices 25. Having set up the example to be performed and having positioned the carriage so that the highest order of the dividend corresponds in ordinal position with the highest order of the divisor, (provided the divisor is not larger than the corresponding figures of the dividend) the operator may then turn the actuating crank 22 to rotate the various orders of the dividend corresponding with the various orders of the divisor backwardly for a distance determined by the setting in the various orders of the divisor. In other words, assuming that the highest order of the dividend be set at "8" and the highest order of the divisor at "3", the accumulator 38 will be rotated rearwardly three numeral spaces for each complete revolution of the crank 22. Similar rearward rotation takes place in the other corresponding orders of dividend and divisor in accordance with their settings. During each rotation of the crank 22, the several stop-setting mechanisms are moved toward the setting devices 25 and toward the stepped cams 88, the upper and lower lever members of each stop-setting mechanism moving normally in unison. The setting devices 25 however operate, in accordance with their settings, to impose various restrictions in movement toward the right to the stop setting mechanisms. In the course of the retrograde action of the accumulators 38 their individual registration will either register a figure or cipher equivalent to the divisor setting of the setting device 25 in the corresponding order or will drop below such divisor setting. As for instance if the accumulator 38 registered 8 and the divisor was set for 4, the retrograde action of the accumulator 38 in that order would bring it to 60 register 4, whereas if the divisor was set for 5, the retrograde action would leave a registration of 3, which would be less than the divisor setting. Assuming, however, that in the course of such retrograde action the registration becomes equal to the divisor set-

ting, the feeler hook of the companion stop-setting mechanism is arrested by said accumulator cam step before the upper lever member 84 of the stop setting mechanism has reached the limit of its movement determined by the setting of the device 25. When this takes place, the lower lever member 82 is shifted about the pivot 85 relatively to the upper member 84, so that the pin 81 causes the upper arm of the stop lever 71 to travel toward the right and the trigger 75 toward the left just sufficiently to release the trigger arm 74 of the stop lever in the next lower order. The movement at this time, however, is not great enough to throw the stop arm 72 into the path of the abutment 68 on the power shift. Should a step 89 corresponding with a digit of the accumulator less in value than that determined by the setting device 25 be presented to the feeler hook during the movement of the stop-setting mechanism, as would happen in the event the remainder figures fell below the divisor figures, the relative movement of the lower lever member 82 would then be great enough to shift the stop arm 72 into the path of the corresponding abutment 68, provided that the stop lever 71 is released by the operation of the trigger of the next higher order, in the manner just described. Consequently as each locking lever 71 is controlled by the operation of the locking lever of the next higher order and thus controls the operation of the locking lever of the next lower order, a movement to stop the main power shaft cannot take place until the remainder has been reduced in value below the divisor. In other words, the mere dropping of an individual digit of the remainder below a corresponding digit of the divisor while any digit of a higher order in the remainder is greater than a digit in the corresponding higher order of the divisor would not effect the operation of the stop mechanism. Ofttimes in division the highest digit in the divisor is greater than the digit in the highest ordinal place in the dividend and, as in mental calculation, the divisor or dividend must be set over, leaving the highest place in the dividend to the left of the highest place in the divisor. It is usual in such cases to set the carriage over to the left one space, which is the equivalent to setting the divisor one place lower or to the right. Under such conditions the stop lever 71 cooperating with the highest order setting device 25 for the divisor must be controlled until the highest order wheel of the dividend reaches 0 in its retrograde action of division. Thus an extra set of stop setting levers 82-84 are provided to co-act with the stepped cam 88 and with a fixed pin located on the underside of the top plate 11 in the same location of its order as the setting devices 25 hold in their respective orders when set at zero. Thus until the over-

flow wheel of the dividend setting reaches 0, the left-most trigger 76, operated by these extra stop setting levers, will not allow any of the lower stop levers 71 to move into stopping position. The springs 104 permit the lower lever members 82 to yield without moving the stop arms to shaft-arresting position, whenever the levers 71 are held out of such position by the triggers 75 of the next higher orders.

Whenever a stop arm 72 is projected into the path of an abutment 68, the operation of the shaft 18 is automatically arrested and cannot be resumed until the stop levers 71 are restored to normal position. This may be effected by a slide bar 107 having pins 108 for the various stop levers 71 and arranged, when the slide bar 70 is shifted toward the right, to engage the depending stop arms 72 of the levers 71 and to restore them to normal position, with the trigger arms 74 latched under the triggers 75 of the next higher orders. The release bar 107 is provided with an operating handle 109 which extends through a slot in the top plate of the main casing. A spring 110 connecting said bar with the left hand side plate maintains the bar in normal position so that the pins 108 are held out of engagement with the stop levers 71.

Provision is made for preventing a lifting movement of the carriage 11 during the operation of the stop-setting levers and until the crank has reached the neutral position to prevent damage to the levers. Referring to Figs. 4, 6 and 9 a latching hook 111 is pivoted at 112 on the right side of the frame and is arranged to hook over the forward edge of the carriage plate to prevent lifting of the same. A spring 113 connecting said last hook with a fixed portion of the frame operates to retract the hook normally out of its locking position. Projecting laterally from the hook 111 is an arm 114 carrying a roller 115 which bears against a cut away surface 116 formed on an arm 117 projecting from the right hand side of the rocker assembly 95. During the operation of the crank 22, the rocker assembly 95 is rocked toward the right by the cam 102 and such movement will force the cut away face 116 into engagement with the roller 115 of the locking hook 111 to move the latter rearwardly into its locking position. When, however, the crank 22 is at normal, the surface 116 has been moved out of the path of the roller 115 to permit the spring to retract the hook 111 into inoperative position.

A further safeguard in the form of locking means is also provided whereby the operating crank 22 is locked against rotation whenever the carriage 12 is lifted thus preventing the stop-setting levers from being thrown under the accumulators and thus damaged by return of the carriage. As shown

in Fig. 7, the rearward end of the drum shaft of the lowest order of the actuating mechanism is provided with a ratchet 118 cooperating with a pawl 119 mounted on a stub shaft 120. Also mounted on the stub shaft 120 is an upstanding arm 121 connected by a spring 122 with a fixed stud 123 projecting from the frame. The spring 122 acts in a direction to rotate the shaft 120 so as to cause the pawl 119 to engage a tooth of the ratchet 118 and prevent rotation of the drum shaft, with the result that the crank 22 is locked against rotation. Fixed on the shaft 120 is an arm 124 adapted to be engaged by the supporting plate 125 for the accumulator gears. When the carriage is lowered into operative position with respect to the actuator mechanism, the plate 125 will depress the arm 124 and cause the shaft 120 to rotate against the power of the spring 122 to lift the pawl 119 out of locking engagement with the ratchet 118.

The invention as hereinabove set forth may be variously embodied within the scope of the claims hereinafter made.

What is claimed is:

1. The combination of a dividend register, a setting register, means for operating the dividend register, and means controlled by the dividend register and the setting register for arresting the motion of the said register when the remainder is less than the divisor.

2. In a calculating machine for performing division, in combination: a series of registering wheels adapted to be set to indicate the dividend; actuating devices for said registering wheels; driving means for said actuating devices; setting devices respectively cooperating with said actuating devices for permitting predetermined actuations of the dividend registering wheels; stop mechanisms for arresting the motion of the driving means and corresponding to the actuating devices, each stop mechanism being controlled by the stop mechanism of the next higher order and itself controlling the operation of the stop mechanism of the next lower order; and ordinal stop-setting mechanisms companion to the respective stop mechanisms each stop-setting mechanism being controlled by the adjustment of the setting device and the dividend registering wheel of its corresponding order; substantially as specified.

3. In a calculating machine for performing division, in combination: registering mechanism adapted to be set to indicate the dividend; actuating mechanism for said registering mechanism; means for setting said actuating mechanism to permit predetermined actuations of the registering mechanism; means for indicating the quotient value; stop mechanism for arresting the motion of the actuating mechanism; and stop

setting mechanism controlled both by the adjustment of the registering mechanism and the actuating mechanism; substantially as specified.

5. In a calculating machine for performing division, in combination: a series of registering wheels adapted to be set to indicate the dividend; stepped cams respectively driven by said registering wheels; actuating devices for said registering wheels; setting devices respectively cooperating with said actuating devices for permitting predetermined actuations of the dividend registering wheels; stop mechanisms for arresting the motion of the actuating devices, each stop mechanism being controlled by the stop mechanism of the next higher order and itself controlling the operation of the stop mechanism of the next lower order; ordinal 70 stop setting mechanisms companion to the respective stop mechanisms to actuate the same, said stop setting mechanisms respectively being operated to release their controlled stop mechanisms when a setting of 75 the registering wheel cam corresponds with a setting of the setting device in the same order; and means for periodically shifting said stop mechanisms into position for being engaged by the setting devices and the 80 registering wheel cams; substantially as specified.

5. In a calculating machine for performing division, in combination: a series of registering wheels adapted to be set to indicate the dividend; actuating devices for said registering wheels; setting devices respectively cooperating with said actuating devices for permitting predetermined actuations of the dividend registering wheels; another series 85 of registering wheels for indicating by operations of said driving means the quotient value in each order; and means for arresting the motion of said actuating devices whenever the remainder in the dividend 90 registering wheels is less in value than the divisor set up in the actuating devices; substantially as specified.

6. In a calculating machine for performing division, in combination: calculating 50 mechanism including a dividend register, a quotient register and a divisor register; means for setting up the dividend and the divisor in their respective registers; driving means for said calculating mechanism; and 55 means controlled both by the dividend register and by the setting in the divisor register for arresting the motion of said driving means; substantially as specified.

7. In a calculating machine for performing division, in combination: calculating 60 mechanism including a dividend register, a quotient register and a divisor register; means for setting up the dividend and the divisor in their respective registers; driving 65 means for said calculating mechanism; and

means for arresting the motion of said driving means whenever the remainder in the dividend register is less in value than the divisor in the divisor register; substantially as specified.

8. In a calculating machine for performing division, in combination: calculating mechanism including an ordinal dividend register, an ordinal quotient register and an ordinal divisor register; means for setting up the dividend and the divisor in their respective registers; a unitary driving means for said calculating mechanism; ordinal driving-means arresting devices, each arresting device controlled by the arresting device of the next higher order, and also controlled both by the operation of the dividend register and by the setting in the divisor register; substantially as specified.

9. A calculating machine that performs 85 division, comprising a calculating mechanism, means for setting up the numerical dividend and divisor in said calculating mechanism and means, controlled by the dividend remainder and the divisor setting, 90 for automatically arresting the motion of the calculating mechanism, whereby the operation of the calculating mechanism is stopped whenever the dividend remainder becomes less in value than the divisor, substantially 95 as specified.

10. The combination of a main drive shaft, bevel gears thereon, bevel gears driven by said gears, squared shafts driven by said gears, drums on said squared shafts having 100 teeth of graduated lengths, pinions adjustable along said drums and driven by the teeth of the latter, squared shafts on which said pinions are adjustable and driven by said pinions, slidable setting devices for adjusting said pinions, a fixed series of digits for said setting devices indicating the number of teeth on said drums which will actuate the pinions, Geneva wheels on said pinion shafts, cooperating cams slidable on said 110 drum shafts whereby the pinion shafts are normally held from rotation and are released to be turned by said drums and pinions, oppositely arranged bevel gears slideable on said pinion shafts, accumulator 115 wheels having gears adapted to be driven forward or backward by said gears, a rock bar for adjusting said gears, carrying mechanism between the accumulator wheels, an accumulator for displaying the quotient, 120 and automatic means for stopping the operation of the accumulators which is caused to operate by the remainder in the first accumulator being less than the divisor indicated by said slidable setting devices.

In testimony whereof we have hereunto set our hands.
